UNITED STATES PATENT OFFICE.

HERBERT E. ENSLIN, OF MALDEN, MASSACHUSETTS, ASSIGNOR TO UNITED SHOE MACHINERY COMPANY, OF PATERSON, NEW JERSEY, A CORPORATION OF NEW JERSEY.

KNOT-TYING MECHANISM.

1,170,885.

Specification of Letters Patent.

Patented Feb. 8, 1916.

Original application filed January 30, 1908, Serial No. 413,343. Patented June 25, 1912, No. 1,030,573. Divided and this application filed April 15, 1911. Serial No. 621,329.

To all whom it may concern:

Be it known that I, HERBERT E. ENSLIN, a citizen of the United States, residing at Malden, in the county of Middlesex and State of Massachusetts, have invented certain new and useful Improvements in Knot-Tying Mechanisms, and I do hereby declare the following to be a full, clear, and exact description of the invention, such as will enable others skilled in the art to which it appertains to make and use the same.

The present invention relates to a knot tying mechanism, and more particularly to a knot tying mechanism of the type in which the knot is formed by forming a loop in the cord or cords and drawing an adjacent portion of the cord through the loop.

The object of the invention is to improve the construction, arrangement and mode of operation of knot tying mechanisms of this type.

With the above object in view, certain features of the invention relate to a novel construction and arrangement of the loop forming mechanism and the parts which co-operate therewith to form the knot.

A further feature of the invention contemplates the provision of means for gripping the cord on the side of the knot opposite the knot forming mechanism during the tightening of the knot so that the tension put upon the knot is not affected by the amount of slack in the cord. The tightening of the knot is preferably affected by the movement of the knot forming mechanism away from the gripping means.

The present invention may be embodied in various machines in which the knotting of a cord or cords is effected, the specific construction and arrangement of parts being modified to co-operate with the other mechanisms with which the knotting mechanism is combined. In an application filed Jan. 30, 1908, Serial No. 413,343, upon which Patent No. 1,030,573 was granted June 25, 1912 I have shown a knotting mechanism constructed and arranged to co-operate with mechanism for lacing together

quarters of shoe uppers and this mechanism is especially designed to co-operate with the other parts of this machine and to tie the ends of the lacing together in a certain and satisfactory manner. The present invention is a division of the above application No. 413,343 and the knot tying mechanism shown in the drawings is the same in specific construction and arrangement of parts as the mechanism shown in that application.

In the drawings, Figure 1 is a side elevation of the knotting mechanism, certain parts thereof being shown in section; Fig. 2 is a front elevation of the parts shown in Fig. 1; Fig. 3 is a section taken on the line *w-w* of Fig. 1; and Fig. 4 is a sectional view taken on the line *v-v* of Fig. 2.

The machine of the application above referred to is provided with a pair of grippers 1 and 2, by which the ends of the lacing are held and a guide bar 3 having a notch 4, in which the cords are retained after the completion of the lacing operation. The knotting mechanism of the present invention is located between said grippers and the guide bar and operates upon the laces or cords extending between the grippers and the guide bar. In the construction shown, the knotting mechanism is constructed to form a loop in the lacing cords, and to draw a bight of the cords through the loop, and to then tighten the knot thus formed. As shown in Figs. 2, 3 and 4, the knotting mechanism is provided with a looping post 5 formed by the lower ends of two semi-cylindrical members 6 and 7. These members are mounted in a sleeve 8, and are provided at their lower extremities with co-operating jaws 9 and 10 for gripping the cord. During the tying of the knot the members 6 and 7 are rotated to form a loop about the post 5, and are also moved longitudinally to grip the cord between the jaws 9 and 10 and draw it through the loop. The sleeve 8 is rotated to impart rotary movements to the members 6 and 7 through a pinion 11 which is engaged by a segmental gear 12. This gear is formed on the front

85
90
95

end of a lever 13, the rear end of which is acted upon by a suitable cam, not shown. The members 6 and 7 are connected to the sleeve 8 by means of a bar 14 extending 5 through a slot 35 formed in the adjacent faces of the members, so that the members will rotate with the sleeve while being free to move longitudinally therein. Longitudinal movements are imparted to the members 6 and 7 by means of levers 15 and 16, the forward ends of which are connected to the members, and the rear ends of which are engaged by suitable cams, not shown.

The looping post 5 is provided with a cord 15 retaining latch 17 which is formed upon a slide 18. The slide 18 is mounted in a transverse recess in the inner face of the member 6, so that the latch is moved radially of the looping post by the sliding movements of the slide. The latch is so formed that when the end of the latch is in engagement with the looping post, an eye 19 is formed at the side of the post in which the lacing cord lies during the formation of the 25 loop on the looping post. A half sleeve 20 is secured upon the lower end of the sleeve 8, and is provided at its lower end with a finger 21 arranged to lie within a slot in the member 7, and to act to strip the loop of 30 cord off the looping post when the post is drawn upward within the sleeve. The sliding latch 17—18 is operated to move the end of the latch toward and away from the post 5, and to retain the latch in either open or 35 closed position by means of cam surfaces 22 and 23 formed on the sleeve 20 and arranged to coöperate with cam surfaces 24 and 25 formed on the latch.

In the operation of the knot tying mechanism, the members 6 and 7 are moved downward to carry the looper post 5 and latch 17 on opposite sides of the ends of the lacing cord, and thus bring the lacing cord into the eye 19 between the latch and post. After 45 the lower end of the latch 17 has passed below the lacing cord, the cam surface 25 engages the cam surface 23, and the latch is moved radially toward the looping post, so that its lower end engages the post, thus 50 closing the eye 19. The latch is locked in this position by the surfaces 25 and 23 during the rotation of the post to form the loop, and until the post is raised to cast off the loop, at which time the cam surfaces 24 55 and 22 act to open the latch so that the loop is free to pass off the looping post. The above described arrangement permits the latch to lie close to the looping post and thus contributes to the compactness of the knotting mechanism. By constructing the latch to slide, and providing means for locking it in position, the construction of the knotter is simplified and its action rendered certain 60 by preventing opening of the latch under

pressure exerted thereon by the cord in the 65 knotting operation.

After the knotting mechanism has moved into position to act upon the lacing cord and the latch on the looper post has closed over the lacing cord, the upper falls away from 70 the lacing mechanism carrying the cords out of the notch in the guide bar 3. The two strands of the lacing cord leading from the grippers 1 and 2 and passing through the eye 19 of the knotting mechanism to the 75 upper then lie against a lateral extension 26 formed at the lower end of the bar 3. This lateral extension extends below and in front of the knotting mechanism, and is provided with a forwardly projecting pin 80 27 which prevents the lacing from swinging too far to the right. The front face of the extension 26 is grooved, and forms a fixed jaw against which the lacing is gripped by a clamping plate 28 during the 85 knot tightening operation. The clamping plate 28 is formed on the forward end of a sliding bar 29 which is operated to give the proper movements to the clamping plate through a lever, the upper end of which 90 is connected by a link 36 with the rear end of the bar, and the lower end of which is acted upon by a suitable cam, not shown.

The clamping plate 28 not only acts to grip the lacing cord during the knot tightening operation, but it is also utilized as a means for controlling the opening and closing of the gripper jaws mounted on the thread arm 37, which act to grip the ends of the lacing cord and carry the cord into 100 position to be engaged by the jaws 9 and 10 of the knotting mechanism, as will be more fully described.

The gripping device for gripping the ends of the lacing and placing them in the jaws 105 of the knotting mechanism consists of a fixed jaw 30 which extends rearward from the lower end of the thread arm 37, and a movable jaw 31 arranged to coöperate with the fixed jaw. The movable jaw 31 is in the 110 form of a thin plate arranged to overlie the jaw 30, and provided with an upturned front end for guiding the lacing cord between the jaws, and with a finger 32 arranged to project down at the side of the jaw 30 and position the cord between the jaws. The gripping plate 31 is pivoted on the thread arm 37, and is provided with a depending operating arm 33. The gripping plate 31 is forced yieldingly toward the fixed jaw 30 115 by a spring 34. The thread arm is connected by a link with a suitable cam operated lever by which the proper forward and rearward movements are imparted to the thread arm in timed relation to the other 120 parts of the knot tying mechanism.

After the upper has fallen away from the lacing mechanism, the thread arm 37 carry-

ing the gripping jaws 30 and 31 moves rearwardly, the spring jaw 31 of the gripping device passing over the lacing cord between the knot forming mechanism and the clamps 5 1 and 2, and the operating arm 33 of the jaw 31 riding on the plate 28 which is moved rearwardly a short distance at this time, but not far enough to engage the lacing cord. During the continued rearward movement 10 of the gripping device the operating arm 33 rides off the plate 28, so that the spring jaw 31 closes against the lacing and grips the lacing against the fixed jaw 30. Just after the gripping device 30-31 has gripped 15 the ends of the lacing, the grippers 1 and 2 are operated to release the ends of the lacing so that the lacing is taken from the grippers 1 and 2 by the gripping device 30-31. About the time the gripping device 30-31 20 reaches its rearward position, the looping post 5 is rotated, and after it has nearly completed a revolution, the jaws 9 and 10 are opened and pass on opposite sides of the lacing, which has been drawn by the 25 rearward movement of the gripping device 30-31 into position to lie between the jaws 9 and 10 as the looping post completes its rotation. The knotter jaws 9 and 10 are then closed, and are moved upward to draw the 30 lacing through the loop on the looping post which is cast off the ends of the jaws by the finger 21 and the end of the sleeve 20. After the lacing is gripped by the knotter jaws, the gripping device 30-31 is given a further rearward movement to draw the ends 35 of the lacing cord from between the jaws 30 and 31. During the upward movement of the knotter jaws 9 and 10, the clamping plate 28 grips the lacing between the knot and the upper, so that the knot is tightened 40 by the upward movement of the jaws. This insures a uniform tightening of the knot, since the cord is gripped on opposite sides of the knot as the two sets of gripping jaws 45 are moved relatively away from each other.

By placing the ends of the lacing between the gripper jaws by the movement of the gripping device which grips the ends of the lacing, the knot may be formed close to the 50 ends of the lacing, so that there is substantially no waste cord in the ends extending beyond the knot. After the knot is completed and tightened, and the jaws of the knotter have been opened to release the ends 55 of the lacing and allow the laced upper to drop from the machine, the thread arm 37 which carries the gripping jaws 30 and 31 moves rearwardly sufficiently to carry the operating arm 33 of the jaw 31 off of the 60 plate 28, so that the jaw 31 closes against the jaw 30. During the lacing operation, the thread arm 37 moves forward to its outer position thus bringing the operating arm 33 into engagement with the clamping plate

28, and opening the gripper jaw 31 preparatory to the rearward movement of the gripping device to grip the ends of the lacing cord as above described. 65

In the operation of the knot tying mechanism, the knotter jaws first move downward behind the two strands of the lacing cord which lead from the grippers 1 and 2 to the upper, the latch 17 passing in front of and below the lacing, and then sliding inward to retain the ends of the lacing on the 70 jaws of the knotting mechanism. After the completion of the lacing operation, the upper falls down and the cords leading therefrom lie against the lateral extension 26 adjacent the pin 27 and pass from said extension through the eye of the looping post and are held by the gripping devices 1 and 2. The thread arm 37 now moves rearwardly to 75 operate the gripping device 30-31, which grips the ends of the lacing cord and carries 80 them rearwardly. The knotter then starts to rotate, and as it completes its rotation the knotter jaws pass on opposite sides of the ends of the lacing and then close. The knotter jaws are then raised to draw the threads 85 through the loop formed on the looping post, and the clamping plate 28 is operated to 90 clamp the lacing between the knot and the upper during the continued upward movement of the knotter jaws, and during 95 the tightening of the knot. After the knot is completed, the jaws of the knotter open, and the clamping plate moves outward so that the upper falls away from the machine. 100

While it is preferred to employ the construction and arrangement of parts shown and described, it will be understood that this construction and arrangement is not essential to the broader features of the invention and may be varied and modified without departing therefrom. 105

Having explained the nature and object of the invention and specifically described one form of apparatus in which it may be embodied, what I claim is:— 110

1. A knot tying mechanism, having, in combination, a cord gripper arranged to grip the free end of a cord on one side of a knot, a second cord gripper arranged to grip the same free end of the cord on the opposite side of the knot with the remainder of the cord extending beyond the gripper and means to cause a relative movement between the grippers to draw the portion of the cord between them taut and thereby tighten the 115 knot, substantially as described. 120

2. A knot tying mechanism, having, in combination, mechanism to form a loop in the free end of a cord, and to draw a bight of the cord through the loop, and a cord gripper arranged to grip the same free end of the cord on the side of the loop opposite 125 said mechanism with the remainder of the

cord extending beyond the gripper and acting to grip the cord during the tightening of the knot, substantially as described.

3. A knot tying mechanism having, in combination, mechanism for forming a knot in the free end of a cord, a gripper arranged to grip the free end of the cord on the side of the knot opposite the knot forming mechanism with the remainder of the cord extending beyond the gripper, and means to cause a relative movement between the knot forming mechanism and the gripper to draw the portion of the cord between them taut and thereby tighten the knot, substantially as described.

4. A knot-tying mechanism, having, in combination, means to hold the end of a cord, mechanism for forming a loop in the cord and for drawing a bight of the cord adjacent to the loop through the loop, arranged in inoperative position, and means to move the said mechanism bodily as a whole into and out of position to act on the cord, substantially as described.

5. A knot tying mechanism having, in combination, a rotary looping post to form a loop in the cord, cord gripping jaws to draw a bight of the cord through the loop, a gripper arranged to grip the cord on the opposite side of the loop, and means to cause a relative movement between the gripping jaws and the gripper to tighten the knot, substantially as described.

6. A knot tying mechanism having, in combination, a rotary looping post to form a loop in the cord, cord gripping jaws carried by said post to draw a bight of the cord through the loop, a gripper to grip the cord on the opposite side of the loop, and means to cause a relative movement between the gripping jaws and the gripper to tighten the knot, substantially as described.

7. A knot tying mechanism having, in combination, cord grippers arranged to grasp the ends of a cord, rotatable and reciprocating jaws adjacent the cord grippers, a gripping device provided with cord gripping jaws, means for actuating the gripping device to grip the cord and place it in said first jaws, and means for actuating the first jaws, substantially as described.

8. A knot tying mechanism having, in combination, rotatable and reciprocating jaws, a sliding cord retainer mounted to rotate with the jaws and arranged to retain the cord upon the jaws during their rotation and to release the cord after it has been seized by the working faces of the jaws, means to lock the cord retainer in cord retaining position during the rotation of the jaws, and means for actuating the jaws, substantially as described.

9. A knot tying mechanism having, in combination, a rotatable and reciprocating

looping post, cord gripping jaws moving with said post, a gripper provided with cord gripping jaws, means for actuating the gripper to carry the cord into position to be gripped by the first jaws, and means for actuating the jaws, substantially as described.

10. A knot tying mechanism having, in combination, a rotatable and reciprocating looping post, cord gripping jaws moving with said post, means for stripping the loop off the end of the post, a gripper arranged to grip the cord on the side of the knot opposite the said gripping jaws, and means to relatively actuate the jaws and gripper to tighten the knot, substantially as described.

11. A knot tying mechanism having, in combination, rotatable and reciprocating jaws, a sliding latch mounted to rotate with the jaws and arranged to retain the cord upon the jaws during their rotation and to release the cord after it has been seized by the working faces of the jaws, means to lock the latch in cord retaining position, and means for actuating the latch and jaws, substantially as described.

12. A knot tying mechanism having, in combination, means to hold the end of a cord, a knot forming mechanism arranged to act on the cord adjacent the holding means, a device provided with cord gripping jaws arranged to engage the cord between the knot forming mechanism and the holding means and means to actuate said device to grip the cord and take it from the holding means, substantially as described.

13. A knot tying mechanism having, in combination, means for holding the end of a cord, a knot forming mechanism provided with jaws arranged to act upon the cord adjacent the holding means, a gripper provided with cord gripping jaws arranged to grip the cord between said holding means and knot forming mechanism, and means for operating said gripper to grip the cord and place it in position to be gripped by the jaws of the knot forming mechanism, substantially as described.

14. A knot tying mechanism having, in combination, rotary and reciprocating jaws, a sliding latch mounted to rotate with the jaws, and means for sliding said latch toward and from the jaws as the jaws are reciprocated, substantially as described.

15. A knot tying mechanism having, in combination, a rotatable looping post, a cord retaining latch mounted to slide transversely in said post, and means for operating the latch and post, substantially as described.

16. A knot tying mechanism having, in combination, a rotary and reciprocating looping post, cord gripping jaws carried by the post, means for rotating the post to form a loop and operating the grippers to draw

a cord through the loop, and means for gripping the cord on the opposite side of the knot to cause a tightening of the cord between the gripping jaws and gripping means as the jaws move away from the gripping means and thereby tighten the knot, substantially as described.

17. A knot tying mechanism, having, in combination, means to hold the end of a cord, a knot forming mechanism arranged

in inoperative position, and means to move the knot forming mechanism bodily as a whole toward and from the cord into and out of operative position with relation to the cord, substantially as described.
